MACHINE GUN

Val A. Browning, Ogden, Utah, assignor to J. M.
& M. S. Browning Company, Ogden, Utah, a
corporation of Utah

Application October 29, 1940, Serial No. 363,263

5 Claims. (Cl. 89—3)

The present invention relates to automatic machine guns and more particularly to machine guns of the recoil operated, belt feed type.

The object of the present invention is to provide a gun of the above-indicated type wherein the barrel structure may be readily and quickly mounted and dismounted from the breech casing. The advantage of such a structure is that air cooling means may be utilized in conjunction with the barrel, thus eliminating the water cooling means which heretofore have been necessary in guns of the recoil operated type. Another advantage is that the gun may be properly breeched without stripping any of the breech casing.

Another object is to provide a barrel structure incorporating latching means which are automatically operable upon the mounting of the barrel structure upon the breech casing to firmly secure the parts in proper aligned position.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Fig. 1 is a view of a completely assembled machine gun embodying the invention herein;

Fig. 2 is a view partly in section showing the interconnecting and interlocking means between the barrel structure and the breech casing;

Fig. 3 is a plan view partly in section showing details of construction of the connecting means;

Fig. 4 is a partial sectional view of the breech casing with the barrel structure being assembled therein;

Fig. 5 is a perspective view of the forward end of the breech casing with the side plates broken away to show the forward end of the barrel extension;

Fig. 6 is a perspective view showing the forward end of the breech casing;

Fig. 7 is a perspective view of the interlocking end of the barrel structure; and

Fig. 8 is a perspective view similar to Fig. 7, but showing another type of barrel structure.

Referring to the drawings, the invention comprises generally an automatic machine gun having a receiver or breech casing 10, a barrel structure 11 comprising a barrel support 12 and barrel 14 carried thereby, and latching means 15 for securing the removable barrel structure onto the

breech casing 10. The gun is of the type wherein the barrel recoils upon firing of the gun, and the recoil action is utilized to operate the firing, ejecting, and feed mechanism. For purposes of simplicity, no showing of the firing, ejecting, and feed mechanism will be shown, other than such parts as are required for an understanding of the invention herein.

More specifically, the breech casing 10 includes 10 the usual side plates 16 having secured between their forward ends a trunnion block 18 so positioned that its forward face 20 is rearwardly of but parallel to the forward edges of the side plates 16. Intermediate of the trunnion block 15 face 20 and the forward edges of the side plates 16, the inner walls of the latter are cut to provide opposed vertically extending mortices 22 for positioning and interlocking the barrel support 12 to the breech casing 10, as is hereinafter apparent.

20 As in previous recoil operated machine gun structures, there is also slidably mounted in the breech casing a barrel extension 24. Herein the side arms 26 of the barrel extension are joined 25 at their forward upper edges by a cross plate 28 and are open between their lower forward edges. The inner walls of the side arms 26 and the cross plate 28 are machined to an inverted U shape (see Fig. 5), and inwardly from the forward edges the side walls are cut to provide opposed vertically extending mortices 30 for positioning and 30 interlocking the barrel, as is hereinafter apparent.

Referring now to the barrel support 12, it includes a rear barrel receiving member comprising 35 a rectangular block 32 and a forward barrel receiving member comprising a rectangular block 34 interconnected by parallel side plates 36. To interconnect the barrel support 11 on the receiver 10, the rear side edges of the supporting member 40 32 are provided with laterally projecting, vertically extending tenons 38 adapted, upon proper alignment of the barrel support and receiver 10, to be telescoped within the receiver mortices 22 for interlocking the parts together. As indicated, the barrel 14 is carried by the barrel support 11 and mounted in aligned bores 42 provided in the front and rear blocks 34 and 32. The barrel is further provided with a stop member 44 for limiting its movement relative to the support before being mounted onto the receiver. As previously indicated, air cooling means can be used with the barrel of the gun shown therein, and these air cooling means may be of the type shown in the copending application Serial No. 55 363,262 to the same inventor, filed on even date

herewith. When such air cooling means are used, the rearmost heat radiating member of such means would constitute the stop 44.

With the barrel 14 so mounted in the barrel support 12, the rear threaded end 48 of the barrel has threadably mounted thereon a barrel connector 50 for connecting it with the barrel extension 24. The barrel connector 50 comprises an elongated block machined to conform to the inverted U shape of the forward end of the barrel extension 24, whereby it will make a snug fit therewith when positioned in same. To position and interlock the connector 50 within the barrel extension, the connector adjacent its rear end is provided with laterally, vertically extending tenons 52 receivable within the barrel extension mortices 30.

With the above construction it will be seen that upon telescoping the barrel support 11 into the breech casing 10 from the bottom thereof the barrel connector 50 will likewise be telescoped into the barrel extension 24, thereby interlocking and positioning the parts against any movement relative to one another except in the downward direction for disassembly. As best seen in Fig. 3, when the parts are so assembled the trunnion face 20 and the rear face 40 of the barrel support member 32 are in closely abutting relationship with the barrel support 11 and receiver 10 held in rigid alignment.

To facilitate the assembly, the inner walls of the breech casing side plates 16 may have secured thereto oppositely disposed camming members 54 which slant downwardly and rearwardly from the barrel extension mortices 30. The lower front edges of the camming members 54 are positioned rearwardly of the mortices 30 a slightly greater distance than the permissible relative movement between the barrel stop 44 and the barrel supporting member 32, whereby if the barrel should be in its rearmost position upon alignment of the barrel support and breech casing, the barrel connector will engage the cams and be moved forwardly and into proper alignment with the barrel extension mortices 30 (See Fig. 4).

It is obvious from the foregoing that with this construction the barrel support and barrel may be readily assembled with the breech casing and barrel extension without stripping any of the breech mechanism. The use of a separate connector also reduces manufacturing difficulties as it is not necessary to accurately machine the cartridge receiving end of the barrel to breech the gun; the breeching being accomplished by merely rotating the barrel in the connector 50. Moreover, this construction makes it possible to breech the gun without stripping any of the mechanism, for even with the parts assembled the barrel 14 may be rotated within the connector 50 and, when properly breeched, the barrel may be secured by any suitable means, such as a set screw 60 carried in the base of the connector 50 (see Fig. 2).

With the barrel structure assembled onto the breech casing, means must be provided to secure them in assembled position, said means preferably including means for preventing any relative movement of the parts due to lost motion between the interlocking means. For this purpose there is utilized a latching means 15 which not only facilitates assembly, but is automatically operable upon the parts reaching assembled position to latch them together and includes means for rigidly holding the parts against any relative motion, thus assuring accurate alignment at all

times. As best seen in Fig. 2, the latching means comprises a cylindrical bolt 59 mounted in a bore 62 extending forwardly from the face 40 of the rear barrel supporting member 32. Pivotally mounted on the bolt 59 is an operating member 61 having a stem 63 and an operating handle 64 extending forwardly from and at right angles to the stem 61. The forward end of the bolt has a bore, and the stem 63 extends diametrically through the bolt adjacent the rear end of the bolt. The stem is pivoted to the bolt by a pin 61'. The block 32, comprising the rear barrel receiving member of the barrel support, has a circumferential slot 65 through which the stem 63 is adapted to extend, and when this stem is in the vertical position shown in Fig. 1 and the bolt is in its rear or latching position, the rear edge of the stem contacts with, or lies closely adjacent to, the rear face of the slot 65. The upper rear corner 65' between the rear face of the slot and the top surface of the member 32 constitutes a fulcrum point or edge about which the operating member is adapted to pivot as will be hereinafter explained more in detail. The bolt 59 and operating member 61 are normally urged to their rearmost position by a spring 66 having its rear end positioned against the stem 61 and its front end against the base of the bore 62. When so positioned, it will be seen that the rear or latching end 68 of bolt 59 normally extends beyond the face 40 of the member 32. To cooperatively receive the projecting or latching end 68 of the bolt, the face 20 of the trunnion block 18 is provided with a recess 70 into which the bolt end 68 extends to latch the parts together.

In order to prevent any motion of the parts due to any play between the cooperating interlocking members, the spring 66 is sufficiently long to remain under compression when the parts are latched and of sufficient strength to urge the barrel structure forwardly and take up any play between the breech casing and barrel structure interlocking means and prevent any wobbling or loose motion thereof. It is evident that other means could be used.

With the described arrangement, when the barrel structure is detached and is not supported by the handle 64, the bolt and stem 63 are in the full line position shown in Fig. 7. When it is desired to assemble the barrel structure to the breech casing, the barrel structure is lifted by means of the handle, and when this is done, the barrel structure tends to pivot with respect to the stem because the major weight of the barrel structure is forwardly of the stem. During such pivotal movement, the upper rear corner 65' of the slot 60 constitutes a fulcrum with the result that the lower end of the stem will move forwardly thus withdrawing the bolt to its detracted or non-latching position. While the barrel structure is thus supported by the handle, the breech casing may be readily assembled thereon by registering the mortices or grooves 22 of the casing with the mortices or ribs 38 of the barrel support and then lowering the casing (or raising the barrel structure) so as to bring the parts into alignment. At the same time, the connector 48 is properly engaged in the barrel extension 24. After the breech casing is brought into proper aligned position with the barrel support, the casing will rest upon the rear end of the barrel or the connector 50 and, as the breech casing portion of the gun now counterbalances or slightly overbalances the weight of the barrel section forwardly of the stem 63, the stem 63 of the op-

erating handle will swing from the inclined position shown in Fig. 4 to the vertical position shown in Figs. 1 and 2 with the result that the bolt will automatically move from retracted position to the locking position shown in Fig. 2. The gun may now be carried in its assembled condition by means of the handle 64, the weight or forces being so balanced that the operating member does not tend to cant with respect to the barrel support. When it is desired to dismount the casing from the barrel structure, it is merely necessary to grip the handle 64 with one hand and raise the breech casing thereby causing the stem 63 and the barrel structure to cant relative to one another with the result that the bolt is automatically withdrawn from latching position. The casing now may be raised out of engagement with the rear end of the barrel support. As it is necessary to move the operating member 61 out of the line of sight once the gun is assembled, the slot 65 extends laterally to the outer edge of the supporting member 32 and downwardly to below the axis of the bolt 59, whereby with this construction the stem 63 may be moved out of alignment by simply turning it through an angle of 90°.

In order to assist in the holding of the bolt in either of the aforementioned latching positions as well as to give the operator an indication as to when it is in proper position, the latching end 68 may be provided with semi-circular notches 74 spaced 90° apart. When the stem 63 is in proper vertical position, the top and bottom notches 74 will overlie a semi-circular pin 76 vertically arranged in the latching recess 70. Upon movement of the handle through 90°, the bolt will be initially cammed rearwardly sufficiently to clear the top and bottom notches, and when the side notches move to vertical position the bolt spring 66 will again snap the bolt to latching position with the notches overlying the pin 76. When this occurs, a definite click will be heard, thus informing the operator that the handle is in proper position.

As it is desirable in this type of gun to make all parts readily interchangeable, means are provided for readily removing the bolt from the bolt supporting member 32 when the barrel structure is dismounted. To accomplish this, there is provided a second lateral slot 72 extending from the face 40 of the support 32 to the slot 65. As best seen in Fig. 7, the slot 72 is cut on an angle slanting downwardly from the bolt 59, whereby it lies below the normal position of the operating member 61 when the latter is moved out of the line of sight for the firing of the gun. To remove the bolt, the stem 63 is simply rotated until it is aligned with the slot 72, whereupon it may be withdrawn rearwardly through the slot. To normally prevent its being moved to such position, there is provided a lug 67 located on the rear wall of the slot 65 adjacent the base thereof, thus making it necessary to force the stem 61 slightly against the tension of the bolt spring 66 in order to clear the lug before the stem comes into alignment with the slot 72.

Referring now to Fig. 8, the structure shown therein is generally similar to the barrel structure heretofore disclosed. However, in this embodiment the front and rear barrel supports are of circular cross section to support a cylindrical jacket 80. The rear face of the rear barrel support 82 terminates in a rearwardly extending rectangular block 84 provided on its opposite edges with laterally projecting, vertically extend-

ing tenons 86 receivable within the mortices 22 of the breech casing 10. As the structure is otherwise the same as that shown in the prior embodiment, no further description thereof will be made.

As many changes could be made in the above construction and many apparently widely different embodiments of this invention could be made without departing from the scope thereof, 10 it is intended that all matter contained in the above description or shown in the accompanying drawings shall be interpreted as illustrative and not in a limiting sense.

It is also to be understood that the language 15 used in the following claims is intended to cover all of the generic and specific features of the invention herein described and all statements of the scope of the invention which, as a matter of language, might be said to fall therebetween.

I claim as my invention:

1. In a machine gun of the recoil-operated type, a breech casing, a barrel structure having a barrel support, cooperating mortices and tenons on the forward end of said casing and the rear end 25 of said barrel support for demountably connecting the casing and barrel support, a bolt mounted in the rear end of said barrel support and having its rear end engageable with said casing when the bolt is in latching position, an operating member connected to said bolt and having a handle by means of which the demounted barrel support may be carried, and means on the barrel support engageable with said operating member for causing retraction of the bolt when the demounted barrel support is carried by the handle due to the overbalancing weight of the barrel structure forwardly of the operating member.

2. In a machine gun of the recoil-operated type, a breech casing, a barrel structure having a barrel support, vertically extending cooperating mortices and tenons on the forward end of said casing and the rear end of said barrel support whereby the casing and support may be demountably connected together by vertically moving 30 one into alignment relative to the other, a bolt mounted in the rear end of said barrel support and having its rear end engageable with said casing when the bolt is in latching position, an operating member connected to said bolt and having a stem upwardly extending through said barrel support and a handle on the outer end of the stem whereby the demounted barrel structure may be carried, and a fulcrum on said barrel structure engageable with said stem and about 35 which said stem pivots to withdraw said bolt to retracted position when the demounted barrel structure is lifted by said handle, said pivotal movement being caused by the weight of the forward end of the barrel structure.

3. In a machine gun of the recoil-operated type, a breech casing, a barrel structure having a barrel support, cooperating mortices and tenons on the forward end of said casing and the rear end 40 of said barrel support for demountably connecting the casing and support, a spring pressed bolt mounted in the rear end of said barrel support and having its rear end engageable with said casing when the bolt is in latching position, an operating member pivoted to said bolt and having a handle by means of which the demounted barrel support or the assembled gun may be carried, and means on the barrel support engageable with said operating member for moving the latter to retract the bolt when the demounted 45

barrel support is lifted by the handle due to the 50 weight of the forward end of the barrel structure.

4. In a machine gun of the recoil-operated type, a breech casing, a barrel structure having a barrel support, cooperating mortices and tenons on the forward end of said casing and the rear end 55 of said barrel support for demountably connecting the casing and support, a spring pressed bolt mounted in the rear end of said barrel support and having its rear end engageable with said casing when the bolt is in latching position, an operating member pivoted to said bolt and having a handle by means of which the demounted barrel support or the assembled gun may be carried, and means on the barrel support engageable with said operating member for moving the latter to retract the bolt when the demounted 60

barrel support is lifted by the handle due to the 65 weight of the forward end of the barrel structure.

overbalancing weight of the barrel structure forwardly of the operating member.

4. In a machine gun of the recoil-operated type, a breech casing, a barrel structure having a barrel support, vertically extending cooperating mortices and tenons on the forward end of said casing and the rear end of said barrel support whereby the casing and support may be demountably connected together by vertically moving one into alignment relative to the other, a bolt reciprocably mounted in the rear end of said barrel support, the forward end of said breech casing having an opening adapted to receive the rear end of said bolt when the latter is in latching position, an operating member connected to said bolt and having a stem extending generally radially outwardly therefrom and a handle on the outer end of the stem whereby the demountable barrel structure or the assembled gun may be carried, and a fulcrum on said barrel structure engageable with said stem between its ends and about which said stem pivots to withdraw said bolt to retracted position when the demounted barrel structure is lifted by the handle, said pivotal movement being caused by the weight of the forward end of the barrel structure, said stem being pivoted about said fulcrum

in a direction to move said bolt to latching position upon mounting the casing on said barrel structure.

5. In a machine gun of the recoil-operated type, a breech casing, a barrel structure having a barrel support, cooperating mortices and tenons on the forward end of said casing and the rear end of said support for demountably connecting the casing and barrel support together, a bolt mounted for reciprocation in the rear end of said barrel support and having its rear end engageable with said casing when the bolt is in latching position, an operating member pivotally connected to said bolt and having a handle by means of which the demounted barrel support may be carried, a spring within said bolt and between said barrel support and stem, and a fulcrum on said barrel support rearwardly of said stem and engageable with said stem between the ends of the latter, said stem being arranged to pivot about said fulcrum and withdraw the bolt to retracted position when the demounted barrel structure is lifted by said handle, said pivotal movement being caused by the weight of the forward end of the barrel structure.

VAL A. BROWNING.
